FREDRICK W. COFFING, OF PERRYVILLE, INDIANA

CHAIN JACK

Application filed October 5, 1929. Serial No. 397,645.

This invention relates to a power device for association with apparatus such as pike poles, extension props or similar devices, although not necessarily confined thereto.

5 The chief object of the invention is to provide a simple but rugged multiple power construction adapted to receive and elevate an article as indicated.

The chief feature of the invention consists 10 in providing a socket in the form of a tube and slidably mounting therein a plunger, which is operatively associated with a flexible power member, such as a chain, the movement of which causes plunger movement in 15 the socket.

Another feature of the invention consists 20 in the provision of a hinge arrangement between the base and the socket supported thereby and the addition of a latch construction for detachably locking same in an adjusted position.

The full nature of the invention will be 25 understood from the accompanying drawings and the following description and claims:

Fig. 1 is a side elevation of the invention parts being broken away and shown in half section to illustrate the same and other parts in detail. Fig. 2 is a top plan view of the 30 head. Fig. 3 is a transverse sectional view taken on line 3-3 of Fig. 1 and in the direction of the arrows. Fig. 4 is a perspective view of the top of a pike pole shown in the form of a gas pipe with the head mounted 35 thereon. Fig. 5 is a central sectional view through a modified form of base.

In the drawings 10 indicates a base, 11 an 40 elongated tubular socket or column, which is telescopically received in a head 12, having the annular stop portion 13. Flange 13 limits the telescopic movement between the socket and the head. The head 12 includes a pair of outwardly and oppositely extending ears 14, each of which includes an opening 15 for receiving a hook or equivalent construction, the same as desired to be 45 permanently or detachably associated therewith, the latter type of mounting being disclosed herein. Each ear 14 is reinforced by 50 a web 16, so that the lateral load is distrib-

uted throughout the length of the tubular portion of the head, which causes a lateral binding upon the entire length of the tubular socket included within the head.

The tubular socket is provided with a pair 55 of oppositely positioned elongated slots 17, which extend parallel to the axis. A plunger 18 includes a substantial cylindrical head portion, depending from which is a yoke comprising a pair of ears 19 in spaced relation. Each ear includes an aligned opening 20 that supports shaft 21, in turn rotatably supporting sprocket wheel 22. The diameter of this sprocket wheel is greater than the internal diameter of the tubular socket so 60 that wheel teeth 23 extend outwardly into longitudinal slots 17.

A chain anchorage 23 is mounted in one 65 of the openings 15 of the head and is suitably connected as at 24 to one end of the 70 sprocket chain 25. Sprocket chain 25 extends downwardly and toward the socket, passes through the slot 17, engages the lower peripheral portion of the sprocket 22, and then passes outwardly through the opposite 75 socket slot 17 and upwardly to a chain operating mechanism, indicated generally by the numeral 26. The latter is detachably associated with the opposite ear 14 by the anchorage 27 mounted in the opening 15 thereof. While in the present invention said anchorages 23 and 27 are shown of a detachable character the anchorages may be of a 80 permanent character.

The chain operating mechanism is contained within the housing 26 illustrated, and 85 is operated by a hand lever 28. The sprocket chain engages the sprocket wheel 29, mounted in said housing and having the locking dog 30 associated therewith. The sprocket wheel 90 29 is supported by shaft 128 coaxial with the pivotally mounted lever 28. Shaft 128 supports a ratchet 32 engageable by a pawl 33, pivotally supported by a lever 28 and movable therewith. The details of construction 95 and operation of this chain operating mechanism are illustrated, described and claimed per se in the co-pending application entitled "Automatic reverse ratcheting hoist", Serial No. 389,956, filed September 3, 1929. 100

It will be obvious from the foregoing that as the chain is drawn upwardly through the housing 26 the sprocket wheel therein rotates the socket enclosed sprocket 22. For every 5 inch of chain travel the plunger 18 travels one half inch. The load that may be supported by the plunger also is double that which may be supported by the chain if it were applied thereto as described in the beforementioned application.

The chain, as described therein, may be freely pulled through the housing 26 in either direction when not under load, so that the plunger may be freely positioned within the 10 socket. Likewise, the plunger may be advanced under load step by step or may be lowered step by step when under load, and since the chain operating mechanism is of the non-dropping character, the plunger cannot be 15 accidentally released for dropping the load.

The tubular socket is suitably supported by a base or foot portion 35, which may be rigid with the tubular portion 11 but which herein is shown pivotally associated therewith. Base 35 includes an ear 36 and the lower portion of the tube 11 includes a footing 37 that receives the same and includes an ear 38, having an arcuate portion 39. The two ears are coaxially mounted as at 40 and the arcuate surface 39 of one bears upon the surface 41 of the base so that the axle 40 does not entirely support the load. Coaxial with the pivot 40 is a segmental curved rack 42, the teeth of which are adapted to receive a locking tooth 43, carried by arm 44 pivotally supported at 45 upon the base 35. Arm 44 is extended as at 46 and the bell crank lever thus formed is normally tilted, such that tooth 43 engages the arcuate rack 42 for locking the tubular socket in pre-determined relation relative to the base 35. The spring 47 normally maintains the bell crank in locking position.

The tubular housing 11 is adapted to receive a casing pipe pole 60, the bottom end 15 of which bears on the movable support or plunger 18 and the upper end of which projects beyond the central opening in the head 12. Suitably mounted upon as by being receivable by the open end of the pipe 60 is a 20 cap construction having an intermediate bearing portion 61 and a pair of diverging wings 62 and 63. The cap 61 has a portion 66 that is telescopically receivable by the pipe 60. The wing 62 has an outwardly and downwardly directed arcuate upper serrated surface 64 and the wing 63 has upwardly directed arcuate upper surfaces 65.

In Fig. 5 there is illustrated a modified form of base construction which provides 25 limited universal and joint action. In said figure 110 indicates a base plate and 111 indicates the tubular standard. A cap or footing 137 is suitably secured as at 137a to the lower end of the tubular standard 111. The 30 cap 137 terminates in a semi-spherical or

partially spherical base portion 141, and the same is apertured as at 142, and through said aperture extends a pivotal member 140. Suitably secured to the base 110 by passing through the aperture 143 therein and mounting upon the lower end and in the recess 144 of said base a partially spherical faced washer 145 is suitably secured as at 146.

A complementary surface 147 is provided 75 within the cap or foot 141 and a complementary washer 148 bears thereon by a spring 149 suitably supported by the pivot forming a stem 140 through the washer and nut construction 150 and 151 respectively.

Fig. 1 illustrates a relatively adjustable 80 but fixed position arrangement while Fig. 5 illustrates a substantially universal arrangement.

The invention claimed is:

1. In combination a tubular member, a 85 hoist anchorage near the upper end thereof, a unitary hoist capable of independent operation and detachably secured to the anchorage and including a chain, said member having a pair of oppositely positioned slots 90 extending longitudinally of and for a considerable portion of the tubular member, said chain extending through the tubular member and through the slots and having one end anchored to the upper end of the tubular 95 member opposite from the hoist anchorage, a load supporting member longitudinally slidable in the tubular member, and a chain engaging sprocket rotatably supported by and movable with the load supporting member 100 and movable by said chain for moving the load supporting member.

2. In combination a base, a tubular member pivotally connected thereto, a hoist anchorage near the upper end thereof, a unitary 10 hoist capable of independent operation and detachably secured to the anchorage and including a chain, said member having a pair of oppositely positioned slots extending longitudinally of and for a considerable portion 11 of the tubular member, said chain extending through the tubular member and through the slots and having one end anchored to the upper end of the tubular member opposite from the hoist anchorage, a load supporting member longitudinally slidable in the tubular member, and a chain engaging sprocket rotatably supported by and movable with the load supporting member and movable by said chain for moving the load supporting member, the axis of pivotal movement being parallel to the sprocket axis.

3. In combination, a base, a tubular member pivotally connected thereto, a hoist anchorage near the upper end thereof, a unitary hoist capable of independent operation and detachably secured to the anchorage and including a chain, said member having a pair of oppositely positioned slots extending longitudinally of and for a considerable portion 115

of the tubular member, said chain extending through the tubular member and through the slots and having one end anchored to the upper end of the tubular member opposite from the hoist anchorage, a load-supporting member longitudinally slideable in the tubular member, a chain-engaging sprocket rotatably supported by and movable with the load-supporting member and movable by said chain for moving the load-supporting member, the axis of pivotal movement being parallel to the sprocket axis, and means for yieldingly locking the tubular member to the base in an adjusted tilted position.

10 15 In witness whereof, I have hereunto affixed my signature.

FREDRICK W. COFFING.
